UNITED STATES PATENT OFFICE.

LOUIS STEINBERGER, OF BROOKLYN, NEW YORK

INSULATOR.

Application filed February 14, 1919. Serial No. 276,902.

To all whom it may concern:

Be it known that I, LOUIS STEINBERGER, a citizen of the United States, and a resident of the borough of Brooklyn, city and State of New York, have invented certain new and useful Improvements in Insulators, of which the following is a specification.

My invention relates generally to insulators and more particularly to improved means for securing hollow strain members to strain or suspension insulators, and line securing means to line or pin insulators.

The object of my invention is to provide chambered strain members or protruding caps in combination with means for readily securing them in place upon the insulator body so constructed that the securing means may be easily and quickly removed. Other objects will appear from the subjoined specification and claims.

Referring to the drawings:

Fig. 1 is a sectional view of a line or pin type insulator embodying my invention.

Fig. 2 is a side elevation partly in section of another type of strain or suspension insulator embodying my invention.

Fig. 3 is a section on line 3-3 of Fig. 2.

Fig. 4 is a detail in elevation of the form of chambered strain member shown in Fig. 2.

In forming the insulating body I use any suitable insulating material, but I prefer to use that material well known in the art as electrose.

I have shown in Fig. 1 a line or pin type insulator of the usual form having projecting flanges 51 and 52 extending from the body 50 and a stud 53 projecting from the upper central portion thereof. In the central portion of the body is a screw-threaded cavity 54 for the reception of and engagement with the supporting pin (not shown).

The stud 53 is encased in a metal cover 60 having a groove or seat 61 for the reception of the line wire (not shown) and a horizontal groove 62 for the reception of the tie wire (not shown). This metal cover or cap is secured to the stud by the same method and means hereinafter described with respect to the securing of the chambered strain member in Fig. 2; (a description of which in the interest of brevity will suffice for both).

In Fig. 2 I have shown a suspension insulator 70 of disc type which is provided

with a bottom strain member 71 of the usual form which is secured to the central portion of the under side of the insulator body by cement 72 as shown, the strain member being of such form and shape that it fits inside the cavity 73, the cavity being wider at the bottom than at its entrance or mouth, so that the cement is more readily retained in the cavity because of the undercut sides, and the wedge shaped portion 74 on the strain member is more effectually secured to the insulator body.

In assembling the insulator, the body portion is first molded into the shape desired and then the chambered strain members or caps are fitted over the studs or projections extending from the sides or ends of the insulator body so that the circumferential groove in the inner surface of the strain member or cap will coincide with the groove in the side wall of the projection. The holding wire is then placed in this combined groove to lock the metal to the insulation, the construction being such as to enable ready removal of the locking wire or rod and which will be hereinafter described.

The strain member 75 is provided with two projections 76 and 77 with a bolt hole 78 passing therethrough, all for the purposes well understood in this art for securing the insulator to the support or to the next adjacent insulator. The strain member 75 of Figs. 2 to 4 inclusive, and the metal cover 60 of Fig. 1 is each provided on its inner surface with a circumferential groove 79 and likewise there is a groove 80 formed respectively in the projecting portion 70' of Fig. 2 and the projecting portion 53 of Fig. 1 of the insulator body so that when either the chambered strain member 75 or cap 60 is fitted down over the projection 70' or 53 respectively the two grooves will coincide forming a conduit 90. An elongated passageway 91 is provided in the side of the strain member or cap leading into the groove, and the bottom of the groove 80 in the insulator body is provided with a raised projection 92, the said projection 92 being formed by two inclined surfaces 93 and 94 from the bottom of the groove 80 meeting to form the apex of the projection. A wire or rod W is then forced onto the elongated opening 91 in the chambered strain member or cap and is passed into and around the conduit the wire being of such a length that its ends

will each rest rest upon the inclined surfaces 93 and 94. The wire when inserted in the conduit or groove 90 will lock the strain member 75 or cap 60 to the body of insulating material, and the wire may be removed therefrom by inserting a tool in the groove to engage an end of the wire and forcing the wire to move therein, thereby causing the other end of the wire to be lifted upwards by reason of either one of the inclined surfaces 93 or 94 on the bottom of the groove which form the projection 92. The protruding end of the wire may then be grasped by pincers or by any other suitable means and withdrawn from the groove, thus unlocking the hollow cap or strain member from the insulator body.

The diameter of the wire is preferably but slightly smaller than the diameter of the conduit or hole 90, as will be readily understood. The purpose of locking the hollow strain member to the insulator body by means of the wire is that when the insulator is assembled and put into use should it subsequently become injured from any cause whatever, or destroyed, the cap or hollow strain member may be readily removed from the insulator body and applied to a new insulator.

As changes of construction could be made within the scope of my invention, it is intended that all matter contained in the above description or shown in the accompanying drawings shall be interpreted as illustrative and not in a limiting sense.

Having now described my invention, what I claim as new and desire to secure by Letters Patent is:

1. In an insulator of the class described, a body portion of insulating material having a projecting portion provided with a circumferentially extending groove in its peripheral surface the surface of the groove being formed into a projection with inclined sides, a hollow cup shaped socket member into which the projecting portion of said body extends and which member is provided with an internal groove and with an elongated opening in the wall thereof in line with the groove so disposed that the groove of the socket member will register with the groove upon the projecting portion of said body and so positioned that the projection on the groove of the insulator body will be midway of the elongated opening in the socket member, and a locking member located within the space provided by said registering grooves, the ends of the locking member registering with the elongated opening whereby said socket member is locked to the projection aforesaid of said body portion and may be readily removed therefrom.

2. In an insulator of the class described, a body portion of insulating material hav-

ing a projecting portion provided with a circumferentially extending groove in its peripheral surface, the said groove having a projection therein with inclined sides, a socket member into which the projecting portion of said body extends and which member is provided with an internal groove so disposed as to register with the groove in said projecting portion, and an opening leading into said groove opposite the projection on the surface of the first mentioned groove, and a single rod or wire located within the space provided by said registering grooves, the ends of the wire resting upon the sides forming the projection and coinciding with the opening whereby said socket member is removably secured in place.

3. In an insulator of the class described, a body portion of insulating material having a projecting portion provided with a circumferentially extending groove in its peripheral surface, the bottom wall of which has a raised projection provided with two inclined surfaces which meet to form the apex of said projection, a socket member into which the projecting portion of said body extends and which member is provided with an internal groove so disposed as to register with the groove in said projecting portion, and an opening extending into said groove, said opening being located opposite the inclined projection aforesaid in the bottom wall of said groove, and a rod or wire located within the space provided by said registering grooves.

4. In an insulator of the class described, a body portion of insulating material having a projecting portion provided with a circumferentially extending groove in its peripheral surface, the wall of said groove being provided with an inclined projection, a hollow cup shaped socket member into which the projecting portion of said body extends and which member is provided with an internal groove having an elongated opening in the wall thereof leading into said groove, said groove and opening being so disposed as to register respectively with the groove and projection aforesaid upon the projecting portion of said body, and a removable locking member located within the space provided by said registering grooves, the respective ends of said locking member resting upon the projection coincident with said opening whereby said socket member is removably locked to the projection aforesaid of said body portion.

In witness whereof, I have hereunto set my hand at the borough of Manhattan, city and State of New York, this 7th day of February, 1919.

LOUIS STEINBERGER.
In presence of—
C. C. BILLINGS.
